US00D955247S

(12) **United States Design Patent** (10) **Patent No.:** **US D955,247 S**
(45) **Date of Patent:** **** Jun. 21, 2022**

(54) **PET SCALE**

(71) Applicant: **Société des Produits Nestlé S.A.**, Vevey (CH)

(72) Inventors: **William Joseph Vespa**, Quincy, MA (US); **William Broun**, University City, MO (US); **Mark Donavon**, Troy, IL (US); **Kristin Slater**, St. Louis, MO (US); **Ragen Trudelle-Schwarz McGowan**, Saint Joseph, MO (US); **James Collins**, Larkspur, CA (US); **Gregg Robert Draudt**, Stow, MA (US); **Alex Sutton**, Healdsburg, CA (US); **Roberto Vargas**, San Francisco, CA (US)

(73) Assignee: **SOCIÉTÉ DES PRODUITS NESTLÉ S.A.**, Vevey (CH)

(**) Term: **15 Years**

(21) Appl. No.: **29/803,771**

(22) Filed: **Aug. 16, 2021**

(51) LOC (13) Cl. **10-04**

(52) U.S. Cl.

USPC **D10/91; D10/92**

(57) **CLAIM**

The ornamental design for a pet scale, as shown and described.

DESCRIPTION

FIG. 1 is a rear, right perspective view of a pet scale, showing our new design;

FIG. 2 is a front, right perspective view thereof;

FIG. 3 is a rear, left perspective view thereof;

FIG. 4 is a front, left perspective view thereof;

FIG. 5 is a left side perspective view thereof;

FIG. 6 is a right side perspective view thereof;

FIG. 7 is a rear perspective view thereof;

FIG. 8 is a front perspective view thereof;

FIG. 9 is a bottom, left perspective view thereof;

FIG. 10 is a front elevation view thereof;

FIG. 11 is a rear elevation view thereof;

FIG. 12 is a left side view thereof;

FIG. 13 is a right side view thereof;

FIG. 14 is a top plan view thereof; and,

FIG. 15 is a bottom plan view thereof.

The dash-dash broken lines illustrate portions of the pet scale that form no part of the claimed design.

1 Claim, 15 Drawing Sheets
